Primary Examiner — S. Bryan Reinholdt, Jr.*Assistant Examiner* — Andrew D Golson(57) **CLAIM**

The ornamental design for a door stopper for bottom of door, as shown and described.

DESCRIPTION

FIG. 1 is a top, front and left side perspective view of a door stopper for bottom of door showing my new design.

FIG. 2 is a bottom, rear and left side perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof; and,

FIG. 8 is a bottom view thereof.

The door stopper for bottom of door is shown with a symbolic break in its length, represented by broken break lines, that forms no part of the claimed design. The appearance of any portion of the article between the symbolic break lines forms no part of the claimed design.
